TIMING DEVICE

Albert B. Fuller, Rochester, N. Y., assignor to
Eastman Kodak Company, Rochester, N. Y., a
corporation of New Jersey

Application October 7, 1936, Serial No. 104,561

2 Claims. (Cl. 74—142)

This invention relates to timing devices, more particularly it relates to ratchet relays for use in timing devices.

It is an object of this invention to provide a simple and dependable ratchet system which will transform a plurality of impulses into one or more revolutions of a wheel.

It is a particular object of this invention to provide a positive action ratchet pull-down which 10 will rotate a ratchet wheel one tooth or a specified number of teeth at a time.

Other objects and advantages of this invention will be apparent from the accompanying drawing in which:

15 Figure 1 is a perspective view of a device typical of this invention and illustrates the principle thereof.

Figures 2, 3, 4, and 5 are different views of one particular form of this invention. Figure 2 is a front elevation; Figure 3 is a side elevation; Figure 4 is a rear elevation; Figure 5 is a plan.

For clarity, I shall use the terms, horizontal and vertical to describe the relative orientation of the various members of the mechanism of this 25 invention. However, it is to be understood that these terms are merely relative and do not necessarily refer to the actual orientation in space.

In Figure 1, a ratchet wheel 11, having teeth, 11a, 11b, 11c, etc., is propelled, one tooth at a 30 time, by the end 26 of a bar 17 which is substantially horizontal and perpendicular to the plane of the ratchet wheel 11. This bar 17 is pivotally mounted on a support 20 by a pivot 21 so that the bar 17 itself is free to rotate in a 35 horizontal plane. This support 20 is provided with a restraining member 24 which insures that there will be practically no vertical rotation of the bar 17 relative thereto. Pressure exerted downward on the support 20 is thus transmitted by the member 24 to the bar 17. Furthermore, the support 20 is mounted on a base, not shown in this figure, and is hinged along the line 25 so that it is, to a slight degree, free to rotate in a vertical plane. Thus, the end 26 of the bar 17 is permitted both vertical and horizontal movements, and the bar 17 may be considered to be attached through a universal joint to the base mentioned above. These vertical and horizontal movements are confined within the limits defined 50 by two L-shaped members 18 and 19, which are rigidly mounted with respect to the base and the axis of the ratchet wheel 11. A spring 23 which is mounted diagonally in a vertical plane provides tension on the bar 17 so that the end 26 is urged upward and toward the ratchet wheel 11. This

spring 23 is equivalent to two springs, one vertical and one horizontal, and may be replaced by any suitable arrangement which will provide a positive tension having a horizontal and a vertical component.

To operate the device, pressure is exerted downward either directly on the bar 17 or on the support 20 which carries the bar 17. This causes the end 26 of the bar 17 to move downward in engagement with the back face of the tooth 11a 10 until the bar 17 strikes the horizontal portion of the confining member 18. Simultaneously the bar 17 is caused to move laterally by the front face of the next tooth 11b of the ratchet wheel 11 so that it strikes or is very close to the upright 15 portion of the confining member 18 at the same time that it strikes the horizontal portion of the confining member 18. In this final position, the ratchet wheel 11 is unable to rotate in either direction and, hence, cannot overshoot so that 20 it rotates more than one tooth at a time. A detent (not shown in this figure) prevents the ratchet wheel 11 rotating in the opposite direction when the pressure on the bar 17 is released.

When this pressure is released the spring 23 25 causes the end 26 of the bar 17 to move upward until it strikes the horizontal portion of the confining member 19, and horizontally until it strikes the vertical portion of the confining member 19 or the next tooth 11c of the ratchet wheel 11. 30 The vertical portion of the confining member 19 is not essential to this invention. The end 26 of the bar 17 is now in the primary position in its cycle and is ready to engage the next tooth 11b of the ratchet wheel 11. Careful positioning 35 of the confining members 18 and 19 insures that the action through this cycle as described is positive. i. e. that suitable consecutive impulses to the support 20 or directly to the bar 17 will invariably cause the end 26 to engage consecutive teeth of the ratchet wheel 11.

Under some circumstances it may be desirable to have the ratchet wheel move two or any predetermined number of teeth for each impulse received. This may be accomplished by suitable 45 arrangement of the confining members 18 and 19.

Figure 2 shows a particular arrangement of the device shown in Figure 1. A ratchet wheel 11 is mounted to rotate in a vertical plane on an axle 12 which is mounted on a vertical plate 13 which 50 in turn is parallel to the plane of the ratchet wheel 11. A detent 14 is provided to prevent the ratchet wheel 11 rotating counter-clockwise as viewed. The detent 14 is pivoted at the point 15 and is held in contact with the ratchet wheel 11. 55

by a spring 16 in a well known manner. The end 26 of the bar 17 is shown engaging one of the teeth of the ratchet wheel 11. The confining members 18 and 19 described in connection with Figure 1 are rigidly attached to the vertical plate 13 which is provided with a circular hole through which the bar 17 projects. The confining member 18 is mounted on the front face of the plate 13 and the confining member 19 is mounted on the rear face of this plate 13.

Figure 3 shows a side elevation of the particular arrangement of the invention whose front elevation is shown in Figure 2. Similar reference numerals refer to similar elements in all of the drawings. In addition to the parts shown in Figure 2, Figure 3 also shows a support 20 upon which the bar 17 is pivotally mounted by a pivot 21. The support 20 is hingedly mounted, at the point 25, to a base 22 to which the vertical plate 13 is rigidly attached. One end of a spring 23 is attached to the bar 17 as described in connection with Figure 1. The other end is attached at the point 27 to the base 22.

The impulses affecting the bar 17 may be of various types depending on their origin. In Figure 3 an electromagnet 30 provides a convenient method of transforming electrical impulses into mechanical impulses through the support 20 which constitutes the armature of the electromagnet 30.

Referring to Figure 4 which is a rear elevation of the device shown in Figures 2 and 3, one will see that the spring 23 is mounted with its axis diagonal in a vertical plane and is fastened at one end to the bar 17 and at the other end to the base 22 at the point 27.

Figure 5 is a plan or top view of the device shown in Figures 2, 3 and 4. Since similar reference numerals refer to similar parts of the device, a detailed description of this figure would be merely repetitious of that given above.

The reasons why I chose to make this ratchet relay in the manner described and also the important features of my invention will be more clearly understood from the following discussion of the principle underlying its operation.

I have found that an ideal ratchet wheel system is one in which the teeth are symmetrical, have a right angle vertex, and are arranged so that their front and back faces are inclined at an angle of 45 degrees to the adjacent radii of the wheel. For practical purposes any of the radii which intersect a particular tooth may be considered as being adjacent to that tooth since all such radii are within a few degrees of being parallel. Also in this ideal system, the impulse provided by the advancing movement of the propelling member is entirely perpendicular to the back face of the tooth being engaged and parallel to the front face of the next tooth. Furthermore, the return movement of the propelling member must have no lateral component away from the ratchet wheel.

I have also found that most of the advantages of this ideal system can be realized with a modification thereof such as that described in detail above and shown in the accompanying drawing. This arrangement is, at present, more convenient to manufacture than one according to the ideal system would be and it has the added advantage of permitting even greater tolerance to manufacturing errors than the ideal system. It will be noted that this modification follows the ideal system, firstly, in that the front faces of the teeth are inclined to the radii of the ratchet wheel at an angle substantially equal to or greater than 45 degrees,

secondly, in that the impulse provided by the propelling member is also at an angle of 45 degrees to the wheel radii, i. e., parallel to the front faces of the teeth and, thirdly, in that the return movement of the propelling member has no lateral component away from the ratchet wheel. Such a component would probably be due to the front face of the next tooth to be engaged and would cause considerably increased friction with this face.

It has been customary prior to my invention to arrange the engagement between the teeth and the propelling member of a ratchet wheel system so that the impulse provided thereby is as nearly tangential to the wheel circumference as possible, so as to permit a maximum leverage about the center of the wheel and to minimize any component of force toward the center of the wheel. According to my invention, this impulse should be at an angle to the adjacent radii equal to or less than 45 degrees, or more exactly, equal to or less than the angle between this radius and the front face of the next tooth. The best results are obtained when the propelling impulse and the front face of the tooth are substantially parallel and inclined to the adjacent radius at an angle approximately equal to or slightly greater than 45 degrees.

Among the advantages gained by the use of my invention is the fact that the apparatus may be assembled in a relatively loose manner without loss of ability to operate positively. In the drawing, this relative looseness of adjustment is quite apparent from the simple manner in which the support 20 is hinged about the line 25, namely by being held by two hook-shaped knobs on the face 22 which fit loosely into two holes in the support 20 as shown. Furthermore, a ratchet wheel system constructed according to the drawing is inexpensive to manufacture and relatively compact in form. It may be employed wherever these factors are of major importance.

Other arrangements of this invention will suggest themselves to those skilled in the art. Although for the sake of clarity, I have shown and described only one particular form of my invention, I wish to point out that it is not limited to the specific structure shown but is of the scope of the appended claims. For definiteness in the claims the term "adjacent radius" will be taken to mean the radius through the top of the tooth, but obviously such a definition is more critical than the invention requires.

What I claim as my invention and wish to secure by Letters Patent of the United States is:

1. In a ratchet relay assembly, the combination with a ratchet wheel having a plurality of teeth, a detent so mounted that rotation of said ratchet wheel is confined to one direction, a propelling member mounted perpendicular to said ratchet wheel for engagement with the teeth thereof, mounting means movably supporting said propelling member and permitting advancing movement thereof to advance said ratchet wheel, and permitting return movement thereof out of engagement with one tooth of said ratchet wheel into position to engage another tooth of said ratchet wheel, said mounting means also permitting lateral movement of said propelling member with respect to said ratchet wheel, a resilient means connected to said propelling member for returning the same after advancing movement thereof and for laterally urging the same into engagement with the teeth of said ratchet wheel, means for actuating said propelling member to advance said ratchet wheel, two guide members on

opposite sides of said propelling member and for limiting the advancing and return movements thereof and a third guide member positioned near said propelling member to limit the lateral component of its advancing movement so that said propelling member in its most advanced position prevents advancing movement of said ratchet wheel.

5. 2. In a ratchet relay assembly, the combination with a ratchet wheel, a propelling member mounted perpendicular to said ratchet wheel for per-

pendicular lateral engagement with the teeth thereof, mounting means movably supporting said propelling member and permitting movement thereof to advance said ratchet wheel, a resilient means connected to said propelling member for returning the same after advancing movement thereof and for urging the same into engagement with said ratchet wheel and guide members so mounted that the advance and return movements of said propelling member are limited thereby. 10
